The ornamental design for a plant shipping container lid, as shown and described.

DESCRIPTION

FIG. 1 is a top perspective view of the plant shipping container lid shown herein.

FIG. 2 is a front elevational view thereof.

FIG. 3 is a left side elevational view thereof.

FIG. 4 is a top plan view thereof; and,

FIG. 5 is a bottom plan view thereof.

The broken lines in FIG. 1 illustrate unclaimed portions of the plant shipping container lid and form no part of the claimed design.

1 Claim, 3 Drawing Sheets(56)
